CLAIM

The ornamental design for a display holder for brochures and the like, as shown and described.

DESCRIPTION

FIG. 1 is a perspective view of a display holder for brochures and the like, showing my new design; FIG. 2 is a left side elevational view, the right side being a mirror image thereof;

FIG. 3 is a front elevational view thereof;

FIG. 4 is a top plan view thereof;

FIG. 5 is a rear elevational view thereof; and

FIG. 6 is a bottom plan view thereof.

FIGS. 4-6 have been shown on an enlarged scale with respect to FIG. 1.
